INVENTOR.
M. M. McKinney,
BY *James S. Pace*
ATTORNEY.

UNITED STATES PATENT OFFICE.

MERLE MELVIN MCKINNEY, OF LAWRENCE, KANSAS.

DOOR-CONTROLLING DEVICE.

Application filed March 24, 1924. Serial No. 701,499.

To all whom it may concern:

Be it known that I, MERLE MELVIN MCKINNEY, a citizen of the United States, residing at Lawrence, in the county of Douglas and State of Kansas, have invented new and useful Improvements in Door-Controlling Devices, of which the following is a specification.

This invention relates to door controlling devices, being adapted particularly for use in the operation of large and heavy hay mow doors.

The primary object of the invention is to provide means of a simple and improved nature whereby sliding doors may be quickly and easily controlled, moved either to open or closed position, with a minimum of physical effort.

A further object of the invention is to provide a device of this character and for the purpose stated which combines simplicity of construction with efficiency of operation, which involves the use of mechanism so constructed and assembled as to obviate the possibility of breakage or derangement of any of the parts thereof, which requires little or no attention after once being properly installed, and the installation of which may be made at a minimum of cost.

With these and other objects in view, the invention consists of the features of construction, combination and arrangement of parts, hereinafter fully described and claimed, reference being had to the accompanying drawings, in which:—

Figure 1 is a fragmentary elevation, parts broken away, of a familiar type of barn or hay mow and illustrating as applied thereto door operating mechanism embodying the invention,

Figure 2 is a similar view showing the doors in changed position,

Figure 3 is a transverse sectional view taken substantially upon line 3—3 of Figure 1, and

Figure 4 is a fragmentary sectional view on a slightly enlarged scale, taken substantially upon line 4—4 of Figure 2.

Referring now more particularly to the drawings, the barn 5 is provided in an end thereof and in its upper part with a doorway or opening 6, closed by sectional doors indicated at 7 and 8. These doors are of such size as to jointly close the doorway 6 when moved to the limit in one direction,

and which move away from each other when it is desired to open the door.

The covering of the barn in this instance is a pitch roof indicated at 9, and a ridge beam or support 10 constitutes an anchoring means for the upper portions of the roof sides. Supported suitably immediately beneath the roof 9 and adjacent to the wall containing the doorway 6 are tracks 11 within which carriage members 12 travel, and these carriage members are secured at their lower ends to the doors 7 and 8. The trackways 11 are disposed parallel, or substantially so, with those portions of the roof which they underlie, and the tendency of the doors 7—8, therefore, is to gravitate to the outer ends of the trackways.

Each of the doors 7—8 is provided upon its inner surface and adjacent to the upper portion thereof with a pulley 13, over which a cable or rope 14 passes.

One end of the cable or rope 14 is secured as at 15 to the support or ridge beam 10, and from this point of connection the rope passes to and around the pulley 13 of one of the doors; then back to the ridge beam and over guide pulleys 16 carried thereby to and around the pulley 13 upon the opposite door; from whence it passes back to the ridge beam and over a pulley 17 attached thereto. The cable then reaches down to a windlass or drum indicated at 18 in position for convenient manual operation. This windlass or drum may be equipped with an operating handle 19, and a pawl and ratchet mechanism represented generally at 20 to facilitate operation of the device.

It will be observed that the ridge beam or fixed support 10 is positioned midway of the door opening 6, and pull applied to the cable or rope 14 will cause the doors 7—8 to be drawn toward the ridge beam and into closed position. The movement of the two doors is uniform, due to the particular manner in which the cable is trained over the several sheaves or pulleys.

Assuming the doors to be in closed position, as shown in Figure 1, they are maintained so by allowing the pawl of the pawl and ratchet mechanism to remain engaged with the teeth of the ratchet member. When it is desired to open the doors, it is but necessary to withdraw the pawl from engagement with the ratchet teeth, where-

upon the doors will gravitate to open position, as shown in Figure 2. During this operation, it may be advisable to govern the unwinding movement of the windlass, 5 and this may be done either by allowing the operating handle 19 to turn slowly in retrograde direction, or any suitable means may be employed for governing this rotative movement of the windlass. When it is 10 desired to close the doors, the operating handle 19 is grasped and turned in clockwise direction, whereupon the cable will be wound upon the drum and the doors will travel at uniform speed toward each other 15 until they abut in closed position.

From the foregoing it is apparent that I have provided door controlling or operating means which is of exceedingly simple construction, which will operate efficiently, 20 and which enables the movements of the doors to be readily and accurately controlled with but a minimum of physical effort.

While the above is a description of the invention in its preferred embodiment, it 25 will be understood that variations in the construction and arrangement of parts may be resorted to if desired without departing

from the spirit of the invention as defined by the claim.

Having thus fully described my invention, I claim:—

The combination with a building structure having sloping roof sides leading to a ridge beam at the roof peak, and having a doorway in one of the sides thereof intersecting the roof peak, of guide pulleys carried by the ridge beam, trackways mounted on the sloping roof sides, oppositely movable door sections provided with carriages to travel on said trackways, said door sections being movable by gravity to open position, a supporting pulley on the ridge beam, a guide pulley on each door section, a rope or cable fixed at one end to the ridge beam passing around the guide pulley on one of the door sections and over the guide pulleys on the ridge beam, and thence around the guide pulley on the other door section and the supporting pulley on the ridge beam, and a windlass to which the free end of 45 said rope or cable is connected.

In testimony whereof I affix my signature.

MERLE MELVIN MCKINNEY.
